Primary Examiner — Jennifer L Watkins(74) *Attorney, Agent, or Firm* — Goodwin Procter LLP**CLAIM**

The ornamental design for an overlay for drug delivery device, as shown and described.

DESCRIPTION

FIG. 1 is a perspective view of the overlay for a drug delivery device showing our new design;
FIG. 2 is a top view of the design of FIG. 1;
FIG. 3 is a bottom view of the design of FIG. 1;
FIG. 4 is a first side view of the design of FIG. 1;
FIG. 5 is a second side view of the design of FIG. 1;
FIG. 6 is a first end view of the design of FIG. 1;
FIG. 7 is a second end view of the design of FIG. 1; and,
FIG. 8 is a perspective exploded view of the design of FIG. 1.

The broken lines in the drawings showing portions of the drug delivery device and form no part of the claimed design.

1 Claim, 6 Drawing Sheets# US D971,416 S
